REGULATOR VALVE HANDLE

Max L. Jeffrey, Chagrin Falls, Ohio, assignor to Young
Regulator Company, Cleveland, Ohio, a corporation
of Ohio

Filed Aug. 4, 1960, Ser. No. 61,631

Term of patent 14 years

(Cl. D78—1)

FIG. 1 is a top plan view of a regulator valve handle showing my new design;

FIG. 2 is a side elevational view;

FIG. 3 is a bottom plan view thereof.

FIG. 4 is an enlarged sectional view, taken on the line 4—4 of FIG. 1.

I claim:

The ornamental design for a regulator valve handle, as shown.
